(57) **CLAIM**

I claim the ornamental design for a food packaging, as shown and described.

DESCRIPTION

FIG. 1 is a top, right perspective view of a food packaging, showing my new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The hatching used in the drawings represents a contrast in appearance of the claimed design.

The evenly spaced broken lines are for the purpose of illustrating fold lines forming part of the claimed design.

The dot-dash broken lines are for the purpose of illustrating crease lines forming part of the claimed design.
